ATTORNEY.

UNITED STATES PATENT OFFICE.

WILLIAM H. ALISON, OF SAN FRANCISCO, CALIFORNIA.

PISTON-PACKING.

SPECIFICATION forming part of Letters Patent No. 681,383, dated August 27, 1901.

Application filed April 29, 1901. Serial No. 58,058. (No model.)

To all whom it may concern:

Be it known that I, WILLIAM H. ALISON, a citizen of the United States, residing at San Francisco, in the county of San Francisco and 5 State of California, have invented certain new and useful Improvements in Piston-Packings, of which the following is a specification.

My invention relates to an improved packing for piston-heads, the object of my invention being to provide a packing which will avoid leakage to a greater extent than heretofore.

A cylinder will expand unequally in different parts, and in consequence the piston-head is necessarily made considerably smaller than the cylinder, so that packing is necessary to prevent the steam escaping past the piston-head. Heretofore this packing has been accomplished by a snap-ring moving in 15 an annular recess in the piston-head, either with or without a shoulder. If used without a shoulder, the steam would pack the ring and cause undue friction. If used with a shoulder, the piston-head carries the shoul- 20 dered ring with it and causes leakage. My invention enables the packing to follow the walls of the cylinder independently of the 25 position of the piston relatively thereto. My invention also permits of ready adjustment 30 for wear of the surface of the packing.

My invention therefore resides in the novel construction, combination, and arrangement of parts for the above ends hereinafter fully specified, and particularly pointed out in the 35 claim.

In the accompanying drawings, Figure 1 is a diametral section of a packing-ring. Fig. 2 is a similar view of a piston-head, and Fig. 3 is a side view of the packing-ring detached.

Referring to the drawings, 1 represents the piston-head, 2 the spacing-rings therein, and 3 the follower, bolted to the piston-head by

means of the follower-bolts 4. Each spacing-ring has cut therein an annular recess 5, into which is let a compound floating ring, 45 formed of two half-rings 6 bolted together by screws or bolts 7. Said floating ring sections have each an annular shoulder 8, so as to confine a snap-ring 9 in a recess formed by said spacing-ring's sections. The expansive 50 force of the snap-ring causes it to move snugly against the inner surface of the cylinder, and freedom of movement of the snap-ring laterally with respect to the piston-head is permitted by the fact that said snap-ring has a 55 shoulder 10 engaging the annular shoulder 8 of the floating ring and that the floating ring has a clearance on the outside of the spacing-plate. This clearance enables the floating ring to move laterally to any desired 60 extent within given limits relative to the piston-head. Thus the packing can follow the inequalities of the inner surface of the cylinder to any necessary extent. When the outer surface of the snap-ring 9 is worn, the 65 shoulder 10 can be turned down sufficient to provide the necessary tightness of the packing-ring in the cylinder.

I claim—

In an apparatus of the character described, 70 the combination with the piston-head, of the spacing-ring therein having a recess, the floating ring in said recess composed of two sections bolted together, and the snap-ring having a shoulder and supported in said re- 75 cess, substantially as described.

In witnesss whereof I have hereunto set my hand in the presence of two subscribing witnesses.

W. H. ALISON.
